THOMAS S. HOMANS, OF HEMPSTEAD, NEW YORK, ASSIGNOR TO INTERNATIONAL TYPE-SETTING MACHINE COMPANY, OF NEW YORK, N. Y., A CORPORATION OF NEW YORK.

LINE-CASTING MACHINE.

1,123,126.

Specification of Letters Patent. Patented Dec. 29, 1914.

Application filed May 10, 1913. Serial No. 766,822.

To all whom it may concern:

Be it known that I, THOMAS S. HOMANS, a citizen of the United States, residing at Hempstead, in the county of Nassau and 5 State of New York, have invented new and useful Improvements in Line-Casting Machines, of which the following is a specification.

This invention relates to line casting machines, and more especially to those of the linotype class employing a slide carrying a mold disk or wheel and having power means for moving the same toward and from the matrices prior and subsequent to each casting operation. Heretofore, in the operation 10 of machines of this class, the mold-carrying slide is frequently disconnected from its power-operated means and pulled forward for the purpose of cleaning out any accumulated type metal. Practical experience has shown, however, that safety means must be provided to prevent running of the machine, or at least the casting operation, if the operator should attempt to start the machine before the mold-carrying slide has been returned to operative position and again connected to its operating means.

The primary object of the present invention is to provide a control between the main 20 clutch which drives the machine and the mold-carrying slide, which prevents starting of the machine if the mold-carrying slide is disconnected from its power operating means for the purpose of drawing the slide 25 forward and backward by hand for the removal of the type metal which may have leaked from the mouth piece of the metal pot and which prevents disconnecting of the mold-carrying slide from its power operating 30 means while the main driving clutch is engaged.

To this end the invention consists in certain improvements and combinations and arrangements of parts, all as will be herein- 45 after more fully described, the novel features being pointed out particularly in the claims at the end of the specification.

In the accompanying drawing: Figure 1 is a left hand side elevation of a portion of 50 a line casting machine of the well-known linotype class, and equipped with controlling means embodying the present invention, and Fig. 2 is a top plan view of the controlling means.

55 Similar parts are represented by the same reference numerals throughout the views.

One embodiment of the invention is shown in the drawing and will be described in detail in this specification. It is to be understood, however, that the invention is 60 not limited to this particular embodiment of the invention, as equivalent devices may be employed to obtain the same or similar results. In the present instance, the invention is shown, as an example, in connection with 65 a line casting machine of the well-known linotype class, the molds 1 being mounted on a mold wheel or disk 2, and the shaft 3 of this mold wheel is journaled in a bearing 4, which latter is formed as a part of or carried by the mold slide 5. The mold slide is mounted to reciprocate horizontally between guides 6 on the main frame 7, it being understood that in a machine of this class the slide reciprocates to carry the mold to and from a 70 line of matrices held at the forward side of the mold wheel or at the right hand side of the mold wheel as these parts appear in Fig. 1. These reciprocating movements of the mold-carrying slide are effected at proper 75 intervals and by power derived from the cam 8, the latter being driven, as usual, from the main or power shaft of the machine and under the control of the main clutch, which will be hereinafter described. The cam 8 80 coöperates with a roller 9, the latter being mounted on a cam lever 10, this cam lever also carrying a roller 11 adapted to rest in a socket 12 formed at the rear end of the mold-carrying slide. The lever 10 is suspended from a pivot pin 13 on one arm of a hand lever 14, the latter being pivoted to rock on a pin 15. When the parts occupy the full line position shown in Fig. 1, the mold-carrying slide will be operatively connected to cam 8 which operates it. By 85 pressing downwardly on the hand lever 14 and thereby causing the parts to assume the dotted line position shown in Fig. 1, the roller 11 will be withdrawn from the socket 90 12 and hence the mold-carrying slide will be disconnected from its power operating 95 means.

According to the present invention, a safety controller is provided whereby the 100 starting of the machine while the mold-carrying slide is disconnected from its power-operated means, is prevented and it is rendered impossible to disconnect the mold-carrying slide from its power operated means 110 while the machine is running. In the present instance, the controlling means is ap-

plied to the mechanism which governs the operation of the main driving clutch. Machines of this class are usually driven by a pulley 16 which forms one member of a main driving clutch, the other member 17 of the clutch being connected to the main driving shaft 18, and the clutch is engaged and disengaged by a bar 19, one end of which is connected to a clutch controlling lever 20, while the opposite end of this bar is connected to a starting lever 21. The general construction of the main driving clutch and its controlling means is disclosed fully in the patent to Mergenthaler, No. 436,532, dated September 16, 1890. In the present instance, the starting lever 21 is connected to the bar 19 by a toggle 22. When the starting lever occupies the position shown in Fig. 2, the main driving clutch is engaged, and when this starting lever is pushed toward the rear of the machine and in an upward direction with reference to Fig. 2, the main driving clutch is disengaged and the operation of the machine is thereby interrupted. The present invention provides means which prevents the operator from disconnecting the mold-carrying slide from its power operating means while the starting lever 21 is in the running position, as shown in Fig. 2, and also prevents the operator from moving the starting lever into the running position while the mold-carrying slide is disconnected from its power operating means. In the construction shown, the lower side of the bar 19 is provided with a projection 23, a lever 24 is arranged below the bar 19, it being pivoted on pin 25 and provided on its upper side with a tooth or projection 26, and a link 27 is pivotally connected at 28 to the lever 24 and is connected by the pin 29 to the cam lever 10. While the starting lever 21 is in the position shown in Fig. 2, in which position the main clutch is engaged and the machine is running, the tooth or projection 23 on the bar 19 is opposite and immediately above the tooth or projection 26 on lever 24, and therefore it will be impossible for the operator to depress the handle 14 to disconnect the mold carrying slide from the cam lever, for the reason that rising of the cam lever is prevented owing to the connection of the cam lever with the lever 24 by the link 27, the lever 24 being then locked down. When the starting handle 21 is pushed to the rear of the machine or in an upward direction with reference to Fig. 2, this bar 19 will be shifted into the position shown in Fig. 1, the tooth or projection 23 on this lever being then clear of the tooth or projection 26 on the lever 24, and the latter is then free to rise, and the handle 14 may then be oper-

ated to bring the parts into the dotted line position shown in Fig. 1, the mold carrying slide being then disconnected from its power operating means. While the mold-carrying slide is disconnected from its power operating means, it is impossible for the operator to start the machine, as movement of the bar 19 in a direction to start the machine is prevented by the abutting of the tooth or projection 23 thereon against the projection 26 on the lever 24. However, after the mold-carrying slide has been again connected with its power operating means, the bar 19 is unlocked and the machine may be started.

I claim:

1. In a machine of the linotype class, the combination with the driving clutch, means for engaging and disengaging it, the mold-carrying slide, and operating means for the slide capable of being disconnected therefrom, of means to prevent engaging of the driving clutch while the mold-carrying slide is disconnected from its operating means. 85

2. In a machine of the linotype class, the combination with the driving clutch, the mold-carrying slide, and operating means for the slide capable of being disengaged with respect thereto, of means to prevent disconnecting of the mold-carrying slide from its operating means while said clutch is engaged. 90

3. In a machine of the linotype class, the combination with the driving clutch, the mold-carrying slide, and operating means for the slide capable of being connected and disconnected with respect thereto, of means to prevent engaging of the driving clutch while the mold-carrying slide is disconnected from its operating means and to prevent such disconnection while the driving clutch is engaged. 100

4. In a machine of the linotype class, the combination with the driving clutch, the clutch controlling device, the mold-carrying slide, and power operating means for said slide capable of being connected and disconnected with respect thereto, of means co-operating with the clutch controlling device 110 and the power operating means for the slide to prevent engagement of the driving clutch while the slide is disconnected from its operating means and to prevent disconnection of the slide from its operating means while the clutch is engaged. 115

In testimony whereof I have hereunto set my hand in presence of two subscribing witnesses.

THOMAS S. HOMANS.
